Application December 12, 1932, Serial No. 646,934

7 Claims. (Cl. 102—16)

(Granted under the act of March 3, 1883, as
amended April 30, 1928, 370 O. G. 757)

1

This invention relates to a floating support for mechanism to initiate the operation of the firing mechanism of a submarine mine and has for its object to provide a simple yet reliable and effective means for closing the circuit through a sea battery for firing a mine.

With the above and other objects in view, this invention consists in the construction, combination and arrangement of parts as will be described more fully hereinafter.

In the drawing:

Fig. 1 is a side elevation on a float embodying our invention;

Fig. 2 is a diagrammatic view of the float and its connections to the mine;

Fig. 3 is a detail of connection of the cable to the float;

Fig. 4 is a detail of a contact horn and the cup associated therewith.

Various types of mine firing mechanisms have been designed the operation of which depends upon the fact that sea water itself can be used as the electrolyte of an electric battery. They are operated by bringing two dissimilar metals into contact with each other while immersed in sea water, such a device being generally called a sea battery. This is usually done by having a wire of one metal, generally copper, held above the mine case by means of a float and depending upon the hull of a ship, which would ordinarily be of iron, making contact with this wire. However, oftentimes the hull of the ship is rusty or coated with barnacles and the force which the ship exerts upon the wire is so small that metal-to-metal contact is not established sufficiently to complete the sea battery. Another possibility is that the ship may be of wood, in which case contact with the copper wire would have no effect on the firing mechanism. The present invention obviates these difficulties.

The float 5 is of iron or galvanized iron and carries a plurality of iron horns 6 with a reduced portion 7 to permit the horn to be bent laterally by a moderate force. Upon each horn is an iron disk 8 with its edge beveled as indicated at 9 and serrated to form points 10. Disposed around each disk 8 is a copper cup 11 separated from the metal of the float by insulating material 12. To each cup 11 is connected one end of an insulated conductor 13 whereof the other end is connected to an eyebolt 14 secured to the float and insulated therefrom by suitable material 15. An antenna cable 16, preferably of copper, connects eyebolt 14 to the firing mechanism 17 of the mine 18. It is obvious that the cable 16 and

2

eyebolt 14 must be of the same metal, otherwise they would act as a sea battery and explode the mine.

When a horn 6 is bent, as indicated at 6' and 8', by contact with a vessel, the points 10 of disk 8 are easily forced into the copper of the cup 11, thus establishing a good metal-to-metal contact between the copper and the iron of the disk, which, since the sea water acts as an electrolyte, causes a current to flow through the water from the float to the copper plate 19 on the mine as indicated by the arrow and dotted line in Fig. 2. The current is conducted from plate 19 to the firing mechanism 17 where it acts to close the switch of the firing circuit and thence upwardly through cable 16 and conductors 13 to the cups 11, thus completing the circuit.

In our device the float itself forms one electrode of the sea battery, the other being the copper plate 19, and the mine will be fired regardless of the kind of material that strikes the horn. This makes it possible for the mine designer to choose the metals of which the sea battery electrodes are formed, since they are independent of the ship's hull. For example, if the float is galvanized, the effective metals will be zinc and copper instead of iron and copper. Other metals may be used, but it is obviously advantageous to choose two that are considerably separated from each other in the electromotive series.

It will be understood that the above description and accompanying drawing comprehend only the general and preferred embodiment of our invention, and that various changes in the construction, proportion and arrangement of parts may be made within the scope of the appended claims without sacrificing any of the advantages of this invention.

The invention described herein may be manufactured and used by or for the Government of the United States of America for governmental purposes without the payment of any royalties thereon or therefor.

We claim:

1. In combination with a submarine mine body, a device for firing submarine mines, comprising a metal float, a plurality of readily bendable metal horns thereon, a disk having a serrated edge carried by each horn, a metal cup disposed around each disk and mounted on said float but electrically insulated therefrom, the metal of said cups having a position in the electromotive series of metals different from that of the metal of said float, a plate of the same metal as that of said cups secured to said mine body, firing mechanism

in said body, conducting means connecting said plate and said firing mechanism, and conducting means connecting said cups and said firing mechanism.

2. In combination with a submarine mine body, a device for firing submarine mines, comprising a metal float, a readily bendable horn thereon, a disk having a serrated edge carried by said horn, a metal cup disposed around said disk and mounted on said float but electrically insulated therefrom, the metal of said cup having a position in the electromotive series of metals different from that of the metal of said float, a plate of the same metal as that of said cup secured to said mine body, a firing mechanism in said body, conducting means connecting said plate and said firing mechanism, and conducting means connecting said cup and said firing mechanism.

3. A device for firing submarine mines, comprising a buoyant member formed of metal, readily bendable metal horns thereon, a disk having a serrated edge carried by each horn, a cup formed of a metal different from that of said member disposed around each of said disks, a plate of the same metal as that of said cup spaced from said member, a firing mechanism, means electrically connecting said plate and said mechanism, and means electrically connecting said mechanism and said cups.

4. A device for firing submarine mines, comprising a buoyant member formed of metal, elements formed of a different metal carried by said member but electrically insulated therefrom, a plate of the same metal as said elements spaced from said member, a firing mechanism, means electrically connecting said mechanism and said plate, means electrically connecting said mechanism and said elements, and metal elements mounted on said buoyant member in electrical connection therewith adapted to be displaced by contact with a moving object to form a metal-

to-metal contact with the first mentioned elements.

5. A device for firing submarine mines, comprising a buoyant member formed of metal, metal elements carried thereby but electrically insulated therefrom, a plate of metal different from that of said member spaced from said member, a firing mechanism, means electrically connecting said mechanism and said plate, means electrically connecting said mechanism and said elements, and means on said member in electrical connection therewith displaceable by contact with a moving object to form an electrically conducting contact with said elements.

6. A device for firing submarine mines, comprising a buoyant member formed of metal, a plate of a different metal spaced therefrom, a firing mechanism, means electrically connecting said plate with said mechanism, electrically conducting means connected to said mechanism and extending to said member, metal elements carried by said member but insulated therefrom and connected to said electrically conducting means, and displaceable metallic means on said member in electrical connection therewith adapted to penetrate said elements.

7. A device for firing submarine mines, comprising a buoyant member formed of metal, a plate of a different metal spaced therefrom, a firing mechanism, means electrically connecting said plate with said mechanism, electrically conducting means connected to said mechanism and extending to said member, metal elements carried by said member but insulated therefrom and connected to said electrically conducting means, and displaceable metallic means on said member in electrical connection therewith adapted to make electrical connection with said elements.
